(57) CLAIM

We claim the ornamental design for a mini light, as shown and described.

DESCRIPTION

FIG. 1 is a front perspective view of a mini light, showing our new design.

FIG. 2 is a front elevational view of the mini light.

FIG. 3 is a rear elevational view of the mini light.

FIG. 4 is a left side elevational view of the mini light.

FIG. 5 is a right side elevational view of the mini light.

FIG. 6 is a top plan view of the mini light; and,

FIG. 7 is a bottom plan view of the mini light.

The broken lines depict portions of the mini light that form no part of the claimed design. The stippling visible in FIGS. 1 and 2 represent a retro-reflective surface.
